US0D1013865S

(12) **United States Design Patent** (10) **Patent No.:** **US D1,013,865 S**
(45) **Date of Patent:** **** Feb. 6, 2024**

(54) **AUTOMATIC INJECTION DEVICE**

(71) Applicant: **Eli Lilly and Company**, Indianapolis, IN (US)

(72) Inventors: **Delroy George Dennisur**, Smyrna, GA (US); **Hemant Thakorbhai Patel**, Indianapolis, IN (US); **Amin Sedighiamiri**, Carmel, IN (US); **Parker Eugene Trow**, Indianapolis, IN (US); **Hsuan Tsun Wang**, Atlanta, GA (US)

(73) Assignee: **Eli Lilly and Company**, Indianapolis, IN (US)

(**) Term: **15 Years**

(21) Appl. No.: **29/834,283**

(22) Filed: **Apr. 11, 2022**

Related U.S. Application Data

(62) Division of application No. 29/697,944, filed on Jul. 12, 2019, now Pat. No. Des. 958,327.

Primary Examiner — David G Muller

(74) *Attorney, Agent, or Firm* — Arthur Shum

(57) **CLAIM**

The ornamental design for a automatic injection device, as shown and described.

DESCRIPTION

FIG. 1 is a front, top, right perspective view of an embodiment of a button, showing the new design;

FIG. 2 is a rear, bottom, right perspective view thereof;

FIG. 3 is a right-side view thereof;

FIG. 4 is a left-side view thereof;

FIG. 5 is front view thereof;

FIG. 6 is an enlarged front view, as shown in FIG. 5;

FIG. 7 is a rear view thereof;

FIG. 8 is a top plan view thereof; and,

FIG. 9 is a bottom plan view thereof.

The broken lines of even length illustrate portions of the surrounding autoinjector and form no part of the claimed design. The broken lines of uneven length illustrate the boundary of the claimed design and form no part thereof.

1 Claim, 9 Drawing Sheets
